UNITED STATES PATENT OFFICE.

MILLARD F. ANDERSON, OF NEW YORK, N. Y.

BANDING-MACHINE.

1,142,656.

Specification of Letters Patent.

Patented June 8, 1915.

Application filed April 6, 1914. Serial No. 830,054.

To all whom it may concern:

Be it known that I, MILLARD F. ANDERSON, a citizen of the United States, and a resident of the city of New York, Belle Harbor, borough of Queens, in the county of Queens and State of New York, have invented a new and Improved Banding-Machine, of which the following is a full, clear, and exact description.

10 The object of the invention is to provide a new and improved banding machine more especially designed for wrapping one or a series of gummed bands around a roll of oil cloth or other fabric and arranged to feed 15 the bands to the rolls, to cut off the bands to proper length, to moisten the ends of the bands so that when the bands pass onto the peripheral face of the roll to be banded then the forward end sticks to the roll and the 20 rear end overlaps the forward end and is fastened thereto.

A further object of the invention is to print a trade-mark or the manufacturer's name or some other legend on the back of 25 the roll while banding the same.

In order to accomplish the desired result use is made of revoluble supporting rollers 30 for supporting and revolving a roll of oil-cloth or the like, feeding means for feeding gummed bands onto the peripheral face of the said roll, a presser roller for pressing the band into engagement with the peripheral face of the roll, and moistening and feeding means for moistening the band at 35 both ends to cause the forward end of the band to adhere to the peripheral face of the roll and the rear end to overlap the forward end and adhere thereto. Use is also made of a cutting device for cutting the band to 40 proper length, and means for controlling the cutting device and the presser rollers in unison to lift the presser roller off the roll and at the same time cut the bands to proper length.

45 A practical embodiment of the invention is represented in the accompanying drawings forming a part of this specification, in which similar characters of reference indicate corresponding parts in all the views.

50 Figure 1 is a plan view of the banding machine; Fig. 2 is a sectional side elevation of the same on the line 2—2 of Fig. 1; Fig. 3 is an enlarged plan view of the manually-controlled driving mechanism; Fig. 4 is an 55 enlarged sectional rear side elevation of part of the banding machine and showing

more particularly the feeding and moistening device and the printing device, the section being on the line 4—4 of Fig. 1; Fig. 5 is an enlarged cross section of one of the moistening devices for applying moisture to the corresponding moistening cylinder; Fig. 6 is an enlarged cross section of the cutting device for cutting a band to proper length, the section being on the line 6—6 of Fig. 1; Fig. 7 is a plan view of the same; Fig. 8 is a side elevation of the banding machine; Fig. 9 is an enlarged cross section of one of the band-feeding devices, the section being on the line 9—9 of Fig. 1; Fig. 10 is a similar view of part of the feeding and moistening device, the section being on the line 10—10 of Fig. 1; Fig. 11 is a similar view of the same with one of the moistening pads of the moistening cylinder in uppermost position; Fig. 12 is an enlarged cross section of one of the band guides, the section being on the line 12—12 of Fig. 1; Fig. 13 is a similar view of another of the band guides, the section being on the line 13—13 of Fig. 1; and Fig. 14 is a plan view of one of the-banded rolls having a legend printed on the back thereof.

The banding machine is mounted on a suitably constructed main frame A, in which 85 is journaled a transversely-extending shaft B provided with a loose sprocket wheel C over which passes a sprocket chain C' secured at one end to a spring C² attached to the frame A and fastened at its other end 90 to a rod C³ adjustably connected with a bearing C⁴ swiveled in a treadle C⁵ pivoted on the main frame A. The up and down swinging motion of the treadle C⁵ is limited by a suitable stop guide C⁶ attached to the main 95 frame A and having an adjustable screw C⁷ to regulate the amount of throw given to the treadle C⁵. The spring C² normally holds the parts in the position shown in Fig. 2, that is, with the treadle C⁵ raised, and when 100 the operator presses the treadle C⁵ downward then a turning motion is given to the sprocket wheel C in the direction of the arrow a', and this rotary motion of the sprocket wheel C is transmitted to the shaft 105 B by a pawl and ratchet mechanism to rotate the shaft B in the direction of the arrow a'. When the treadle C⁵ is released by the operator then the spring C² returns the parts to normal position, as shown in Fig. 2, without, however, giving a return movement to the shaft B. The pawl and ratchet mecha-

nism referred to consists of a pawl D fulcrumed on the rear face of the sprocket wheel C and engaging a ratchet wheel D' having a head D² secured to the shaft B so that when the sprocket wheel C is turned in the direction of the arrow a' a like movement is given to the shaft B. On the head D² (see Fig. 3) is secured a ratchet wheel D³ adapted to be engaged by a dog D⁴ fulcrumed on the main frame A and normally held out of engagement with the ratchet wheel D³ by a pin D⁵ secured to the sprocket wheel C and projecting transversely therefrom. Thus when the shaft B is turned in the direction of the arrow a' by the sprocket wheel C, the pawl D and the ratchet wheel D' then the pin D⁵ moves from under the dog D⁴ to allow the latter to drop into engagement with the ratchet wheel D³ and to glide over the teeth thereof until the treadle C⁶ reaches lowermost position, and when the spring C² returns the parts to normal position the dog D⁴ holds the ratchet wheel D³ against turning in the inverse direction of the arrow a' thus preventing return movement of the shaft B. When the sprocket wheel C nears normal position the pin D⁵ engages the dog D⁴ and throws the same out of engagement with the ratchet wheel D³. On the shaft B is secured a large gear wheel B' driving a train of gear wheels E, E', E², E³, E⁴ and E⁵, of which the gear wheels E, E', E², and E⁴ are journaled on the main frame A, while the gear wheels E³ and E⁵ are secured on transversely-extending shafts F², F³ carrying rollers F, F' arranged alongside each other to support a roll G of oilcloth or other fabric to be provided with bands H, and an impression I representing a trade-mark or the name of the manufacturer or other suitable legend (see Fig. 14). As shown in this figure, three spaced bands H are applied to the roll so as to hold the same in closed position, but I do not limit myself to the number of bands, as one band, two bands or more than three bands may be used according to the length of the roll G to be banded.

The mechanism for applying the several bands H to the roll G are alike so that it suffices to describe but one in detail. The band material is wound up on a roll or support H' journaled on the main frame A, and the band securely gummed at the inner face unwinds and passes upward from the roll H' over a driven feed roller J and under a presser roller J' located directly above the feed roller J. The feed roller J is secured on a transversely-extending shaft J² journaled in suitable bearings arranged on the main frame A, and one outer end of the shaft J² is connected by a train of gear wheels E⁶, E⁷ and E⁸ with the gear wheel B' on the main shaft B. The feed presser roller J' is mounted on a transversely ex-

tending shaft J³ journaled in suitable bearings J⁴ mounted to slide in vertical guideways A' arranged on the main frame A. Each bearing J⁴ is pressed on by a spring J⁵ so as to hold the presser roller J' with sufficient force in contact with the band material H to feed the same forward whenever the feed roller J is rotated from the main shaft B.

Immediately in front of the rollers J and J' is arranged a cutting device K for cutting the band material H into the proper length so that each cut-off band encircles the roll G with the ends of the band overlapping, as hereinafter more fully explained. Immediately in front of the cutting device K is arranged another set of feed rollers L and L' similar to the feed rollers J, J', of which the feed roller L is secured on a transversely-extending shaft L² journaled in suitable bearings on the main frame A. On one outer end of the shaft L² is secured the gear wheel C⁸ previously mentioned, so that when the shaft B is rotated a rotary motion is imparted simultaneously to the rollers J and L to rotate the same in the direction of the arrows indicated in Fig. 8 with a view to feed the band forward. The roller L' is a presser roller and has its shaft L³ journaled in bearings L⁴ mounted to slide up and down in a vertical guideway A² arranged on the main frame A. A spring L⁵ presses each bearing L⁴ in a downward direction to hold the roller L with sufficient force in contact with the band H to feed the same forward without danger of slipping.

The cutting device K shown in detail in Figs. 6 and 7, consists of a transversely-extending fixed blade K' with which operates a swing blade K² fulcrumed at K³ on the main frame A and pressed on by a coil spring K⁴ to normally hold the blade K² in uppermost inactive position, as shown in Fig. 6. The free end of the swing blade K² is engaged by an eccentric N secured on a transversely-extending shaft N' journaled in suitable bearings arranged on the main frame A. On one outer end of the shaft N' is arranged a crank arm N² connected by a link N³ with a hand lever N⁴ fulcrumed on the forward end of the main frame A to be within convenient reach of the operator. Now when the operator takes hold of the hand lever N⁴ and swings the same rearwardly then a turning motion is given to the shaft N' to cause the eccentric N to swing the blade K² downward against the tension of its spring K⁴ to cut the band H transversely with a view to provide a band of the desired length encircling the roll G and overlapping the ends of the band. The band H during its passage from the feed rollers, J, J' to the cutting device K is guided by a guide O, and a similar guide O' guides the band from the cutting device

K to the feed rollers L and L'. The band H after leaving the feeding rollers L, L' engages a guide O² to conduct the band in a forward direction. The guides O, O' and 5 O² are provided with fingers O³ and the rollers J and L are provided with peripheral grooves J⁶ and L⁶ (see Figs. 1 and 9) into which project the said fingers to insure proper guiding of the bands H close to the 10 sets of feed rollers J, J' and L, L' as possible. The guide O² guides the band H onto the peripheral face of a feeding and moistening cylinder P secured on a transversely-extending shaft P' journaled in suitable 15 bearings on the main frame A. On one outer end of the shaft P' is secured the gear wheel E previously mentioned (see Fig. 8) so that when the shaft B is rotated a rotary motion is given to the cylinder P in the 20 direction indicated by the arrows in Figs. 2 and 8. The cylinder P is provided on its peripheral face with pads P², P³, of felt, sponge or other suitable absorbent material, located diametrically opposite each other to 25 moisten the gummed end portions of the band H so that the forward moistened gummed end of the band H sticks to the peripheral face of the roll H while the rear overlapping end of the band adheres to the outer surface 30 of the forward end. Moisture is supplied to the pads P², P³ by pads Q, Q', of felt, sponge or other absorbent material, mounted on the peripheral face of a cylinder Q² held on a shaft Q³ journaled in suitable bearings 35 arranged on the main frame A. The lower portion of the cylinder Q² extends into a receptacle Q⁴ containing water for saturating the pads Q, Q' during the time the said pads are immersed in the water on rotating 40 the cylinder Q². The receptacle Q⁴ is provided on its ends with hooks Q⁵ (see Figs. 2 and 5) hung onto the shaft Q³ to properly support the receptacle Q⁴ relatively to the cylinder Q². The shaft Q³ of the cylinder 45 Q² is provided on one outer end (see Fig. 8) with a gear wheel Q⁶ in mesh with an intermediate gear wheel Q⁷ journaled on the main frame A and in mesh with the main gear wheel B' so that when the latter is rotated 50 a rotary motion is given to the cylinder Q² to cause the pads Q, Q' to be immersed in the water contained in the receptacle Q⁴ at the same time moving the pads Q, Q' in engagement with the pads P², P³ 55 to moisten the same.

Directly above the moistening cylinder P is arranged a presser roller R for firmly pressing the band H into contact with the peripheral face of the cylinder P to feed 60 the band forward and to press the same firmly in contact with the pads P², P³ to moisten the gummed ends of the band, as previously mentioned. The roller R is secured on a shaft R' journaled in bearings R² mounted to slide up and down in vertical

guideways A⁴ arranged on the main frame A, and each bearing R² is pressed in a downward direction by a spring R³, as plainly indicated in Fig. 8, to cause the roller R to press the band H in contact with the peripheral face of the cylinder P and its pads P², P³. 70

The peripheral face of the moistening cylinder P is provided with grooves P⁴ (see Fig. 10) for receiving on top of the cylinder 75 a number of wires S extending from near the forward end of the guide O² to within a short distance of the roll G to support and guide the moistened band H from the moistening and feed rollers P and R to the roll G. The wires S embed themselves in the pads P², P³ whenever the said pads move into top position (see Fig. 11). The wires S are coiled around a supporting pin S' 80 projecting transversely from a bracket S² secured to the main frame, as will be readily understood by reference to Figs. 2 and 13. The ends of the wires S are turned under to cause the band to readily pass onto the guiding and supporting wires S and to 85 leave the same without danger of displacement of the band. The pin S' supports brackets S³ carrying a top plate S⁴ spaced from the wires S and extending over the band H so as to prevent the same from upward 90 movement during its passage from the moistening and feed rollers P and R to the roll G. It is understood that by the use of the wires S the moistened band is not liable to stick to the said wires as the band has only 95 line contact with each of the wires. 100

In order to press the band H in firm contact with the roll G use is made of a presser roller T located directly above the roll and attached to a shaft T' journaled in arms T² fulcrumed at T³ on the sides of the main frame A. The arms T² are provided with guideways T⁴ in which are mounted to slide bearings T⁵, of which the bearing T⁵ at 105 the front side of the machine (see Fig. 8) is engaged by a pin N⁵ held on the hand lever N⁴ previously mentioned, while the rear bearing T⁶ is engaged by a pin T⁶ held on an arm T⁷ secured on a transverse shaft N⁶ journaled in suitable bearings on the 110 main frame A and carrying the hand lever N⁴. When the hand lever N⁴ is swung rearwardly for actuating the blade K², as previously explained, to cut the band H to the proper length then an upward swinging 115 movement is given to the arms T² to lift the presser roller T and thus allow removal of a banded roll G from the rollers F, F' and to allow an unbanded roll G to be placed in position on the said rollers F, F' 120 to be banded. 125

In order to print the legend I onto the roll G at one end thereof, the following arrangement is made, special reference being had to Figs. 1 and 4: A segmental impres- 130

sion cylinder U is mounted to swing loosely on a stud U' attached to the main frame A at the rear side thereof, and on the peripheral face of the cylinder U is removably secured a printing plate U², of rubber, metal or other suitable material, and containing on its face the desired matter for printing the legend I onto the roll G. The face of the printing plate U² is inked by an inking roller U³, of felt or other suitable material, and saturated with a suitable color. The inking roller U³ is mounted to rotate loosely on the rear end of the shaft F³ previously mentioned. The peripheral face of the cylinder U is provided with a roughened segmental plate U⁴ adapted to be engaged by the peripheral face of the roll G so that when the latter is rotated by the rollers F, F' as previously explained then a swinging motion in an upward direction is given to the impression cylinder U. When this takes place the face of the printing plate U² moves first in contact with the inking roller U³ and is engaged thereby, and then the face of the printing plate U² moves in contact with the peripheral face of the roll G to make an impression thereon, that is, to print the legend I onto the roll G. When the banded roll G is finally removed from the rollers F and F' then the cylinder U by its own weight swings downward back into normal position, as shown in Fig. 4. The downward movement of the cylinder U is limited by a stop bar U⁵ mounted on the main frame A and extending into the path of the upper spoke U⁶ of the cylinder U, as will be readily understood by reference to Fig. 4. On the outer end of the stop bar U⁵ is secured an upwardly-extending stop arm U⁷ against which the rear end of the roll G abuts, thus permitting correct location of the roll G on the rollers F and F'. The operation is as follows: A roll G to be banded is placed in position on the rollers F and F' with the rear of the roll abutting against the stop arm U⁷ and with the presser roller T in uppermost position. The blades K', K² having cut off a band H the latter is fed forward into the guideway O² by the feed rollers L and L' on a previous operation. The operator now swings the hand lever N⁴ downward so that the presser roller T engages the top of the roll G and the knife blade K² returns to uppermost position owing to the action of the spring K⁴. The operator now swings the treadle C⁵ downward so that a rotary motion is given to the shaft B, whereby the feed rollers J, J', L, L', are rotated, likewise the moistening cylinder P, the moisture supplying cylinder Q² and the rollers F, F'. The rotary motion given to the rollers F, F' causes the roll G to rotate in the direction of the arrows indicated in Figs. 2 and 8, and at the same time the cut-off band H is

fed forward by the feed rollers L, L' to pass between the cylinder P and its presser roller R so that the pad P² engages the gummed under side of the band H at the forward end thereof and moistens the front gummed portion at the same time the cylinder P and the presser roller R feed the strip forward over the guide S until the forward end of the band H finally passes onto the peripheral face of the roll G and is pressed in firm contact therewith by the presser roller T. When this takes place the moistened forward end of the band H is caused to adhere to the peripheral face of the roll G and consequently the band H is wound around the roll G. During the rotation of the cylinder P the other moistening pad P³ comes in contact with the gummed under surface of the band H at the rear end thereof and moistens the same, and this moistened rear end of the band H finally overlaps the forward end of the band and is fastened thereto, as will be readily understood by reference to Fig. 2. During the time the roll G is rotated and the band H is caused to encircle the same as described, the printing cylinder U is caused to swing upward and print the legend I onto the roll G at one end thereof, it being understood that the face of the roll G of oilcloth is inward and consequently the impression is made on the back of the oilcloth.

During the forward movement of the cut-off band H the band material is fed forward by the feed rollers J and J' through the guides O, O' and between the knives K', K² so that the forward end of the band material finally engages the presser rollers L, L' and is fed forward by the same along the guideway O² until the forward end of the band material is adjacent the face of the moistening cylinder P, as indicated in Fig. 2. When this position is reached the treadle C⁵ is at the end of its downward stroke, and the operator now releases the treadle C⁵ so that the treadle and the sprocket wheel C return to normal position by the action of the spring C² while the rotation of the feed rollers J, J', L, L', the cylinders P and Q², the rollers F, F' and the roll G ceases. The operator now swings the hand lever N⁴ backward to swing the presser roller T in an upward direction out of engagement with the band H to permit convenient removal of the banded and printed roll G. During this rear movement of the hand lever N⁴ the eccentric N is actuated to cause the blade K² to swing downward to cut the band in conjunction with the blade K', and then another roll G to be banded is placed on the rollers F, F' and the hand lever N⁴ is returned to normal position as shown in Fig. 8, to cause the presser roller T to reengage the roll G at the top thereof and to allow the blade K² to swing upward into inactive

position. The operator now again presses the treadle C^6 when the above described operation is repeated.

From the foregoing it will be seen that 5 while a band H is passed around the roll G a length of band material is fed forward into the guide O^2 corresponding to the proper length of a band for the next roll G to be banded, and the band material is cut 10 by the blades K^1 , K^2 as soon as the operator swings the hand lever N^4 rearward to raise the presser roller T to allow removal of the banded and printed roll G .

It is understood that the trains of gear 15 wheels driven from the main gear wheel B' are so proportioned as to accomplish the desired result.

It will be noted that while the moistening cylinder P makes one revolution at each 20 operation of the machine the roll G makes somewhat more than one revolution to cause the ends of the band H to overlap. But a few simple movements are required by the attendant of the machine and hence a large 25 number of rolls can be accurately banded in a comparatively short time and without requiring skilled labor.

Having thus described my invention, I 30 claim as new and desire to secure by Letters Patent:

1. A banding machine, comprising means for supporting and revolving a roll to be banded, feeding means for feeding a gummed band to the peripheral face of the 35 said roll, a presser roller for pressing the band into contact with the peripheral face of the said roll, moistening means for moistening the ends of the gummed band prior to the band reaching the roll, cutting means 40 for cutting the band to proper length prior to the band reaching the said moistening means and means for actuating the cutting means when the pressure roll is withdrawn from the banded roll at the finish of an 45 operation.

2. A banding machine, comprising means for supporting and revolving a roll to be banded, feeding means for feeding a gummed band to the peripheral face of the 50 said roll, a presser roller for pressing the band into contact with the peripheral face of the said roll, moistening means for moistening the ends of the gummed band prior to the band reaching the roll, cutting means 55 for cutting the band to proper length prior to the band reaching the said moistening means, and means connected with the said presser roller and the said cutting means for simultaneously moving the said presser roller into active position and the said cutting means into inactive position.

3. A banding machine, comprising means for supporting and revolving a roll to be banded, feeding means for feeding a 65 gummed band to the peripheral face of the

said roll, a presser roller for pressing the band into contact with the peripheral face of the said roll and movable to and from operative position in engagement with the roll, moistening means for moistening the 70 ends of the gummed band prior to the band reaching the roll, cutting means controlled by movement of the pressure roll for cutting the band to proper length prior to the band reaching the said moistening means, and feeding means for feeding the band from a roll to and past the said cutting mechanism at the time the latter is in inactive position.

4. A banding machine, comprising pairs of driven rollers adapted to support and rotate a roll to be banded, a presser roller for pressing the band into contact with the peripheral face of the roll, a feeding and moistening device for feeding the band under the presser roller and onto the peripheral face of the roll, the said feeding and moistening device having means for moistening the ends of the band, two spaced sets of feed rollers for intermittently feeding the band from a roll forward to the said 90 feeding and moistening device, and a cutting device intermediate the said sets of feed rollers for cutting the band to proper length when said feeding means are inactive.

5. A banding machine, comprising pairs of driven rollers adapted to support and rotate a roll to be banded, a presser roller for pressing the band into contact with the peripheral face of the roll, a feeding and moistening device for feeding the band under the presser roller and onto the peripheral face of the roll, and said feeding and moistening device having a moistening cylinder provided on its peripheral face 100 with diametrically opposite moistening pads for moistening the ends of the said band, two sets of feed rollers for feeding the band to the peripheral face of the said moistening cylinder, and intermittent driving means 106 for driving the said moistening cylinder and the said sets of feed rollers in unison to cause one moistening pad to moisten one end of the band and the other moistening pad to moisten the other end of the band.

6. A banding machine, comprising pairs of driven rollers adapted to support and rotate a roll to be banded, a presser roller for pressing the band into contact with the peripheral face of the roll, a feeding and moistening device for feeding the band under the presser roller and onto the peripheral face of the roll, the said feeding and moistening device having a moistening cylinder provided on its peripheral face 120 with diametrically opposite moistening pads for moistening the ends of the said band, two sets of feed rollers for feeding the band to the peripheral face of the said moistening cylinder and the said sets of feed rollers in 125 130

unison to cause one moistening pad to moisten one end of the band and the other moistening pad to moisten the other end of the band, and a manually-controlled cutting device intermediate the said sets of feed rolls for cutting the band to a length corresponding approximately to the feeding distance of the said moistening cylinder.

7. A banding machine, comprising pairs of driven rollers adapted to support and rotate a roll to be banded, a presser roller for pressing the band into contact with the peripheral face of the roll, a feeding and moistening device for feeding the band under the presser roller and onto the peripheral face of the roll, the said feeding and moistening device having a moistening cylinder provided on its peripheral face with diametrically opposite moistening pads for moistening the ends of the said band, two sets of feed rollers for feeding the band to the peripheral face of the said moistening cylinder, intermittent driving means for driving the said moistening cylinder and the said sets of feed rolls in unison to cause one moistening pad to moisten one end of the band and the other moistening pad to moisten the other end of the band, and a guide for guiding the band from the last set of feed rollers to the said moistening cylinder.

8. A banding machine comprising means for supporting and revolving a roll to be banded, a pressure roll movable bodily toward and away from a roll disposed upon the said supporting and revolving means, means for intermittently feeding a gummed

strip from a roll, cutting means for cutting the gummed strip into bands of a desired length, means for feeding the cut bands to the roller to be banded, and connections between the said pressure roll and the said cutting means whereby to actuate the latter when the pressure roll is moved bodily toward and away from the roll to be banded at the beginning and end of the banding operation.

9. A banding machine comprising a frame, a pair of driven rollers for supporting and revolving a roll to be banded, a pressure roll, supports for the pressure roll journaled upon the frame to permit the said pressure roll to be bodily moved toward and away from the roll to be banded, a lever pivoted upon the frame and having connection with the said pressure roll supports for moving the latter, feeding means for feeding a gummed strip from a roll, cutting means for cutting the strip into bands of the desired length, means for feeding the bands so cut to the roll to be banded, and connections between the said lever and said cutting means whereby to actuate the latter when the former is moved to raise the pressure roll away from the banded roll at the end of each operation.

In testimony whereof I have signed my name to this specification in the presence of two subscribing witnesses.

MILLARD F. ANDERSON.
